United States Patent Office

Des. 202,196
Patented Sept. 7, 1965

202,196

DESK

Ronald H. Beckman, New York, N.Y., assignor to Herman Miller, Inc., Zeeland, Mich., a corporation of Michigan

Filed Nov. 27, 1964, Ser. No. 82,822

Term of patent 14 years

(Cl. D33—7)

FIG. 1.

FIG. 2.

FIG. 3.

FIG. 6.

FIG. 4.

FIG. 5.

FIG. 7.

FIG. 1 is a perspective view of the desk of my novel design, showing the tambour cover retracted;

FIG. 2 is a perspective view of the desk with the tambour cover extended to its cover position;

FIG. 3 is an end elevational view of the desk;

FIG. 4 is a rear elevational view of the desk with the tambour cover extended;

FIG. 5 is a rear elevational view of the desk with the tambour cover retracted;

FIG. 6 is a sectional view of the desk base, taken on plane VI—VI of FIG. 3; and

FIG. 7 is a front elevational view of the desk with the tambour cover retracted.

The opposite end of the desk to that shown in FIG. 3 has a mirror image appearance of the end shown.

I claim:

The ornamental design for a desk, substantially as shown and described.
